[57] CLAIM

The ornamental design of a handle shaft for a garden or snow tool, as shown and described.

DESCRIPTION

FIG. 1 is a front elevational view of a handle shaft for a garden or snow tool embodying my new design; FIG. 2 is a rear elevational view of the handle shown in FIG. 1;

FIG. 3 is a right side elevational view thereof, the left side elevational view being a mirror image of the right side elevational view;

FIG. 4 is a cross-section of the handle taken along the arrows "4—4" in FIG. 1;

FIG. 5 is a cross-section of the handle taken along the arrows "5—5" in FIG. 1;

FIG. 6 is a perspective view of the rear of the handle; and, FIG. 7 is a side view of the second embodiment of the design shown in FIG. 1 with the opposite side being a mirror image. The undisclosed front and rear views of the second embodiment are similar in appearance to the claimed design except the rear view is devoid of a label.

The broken line showing of a handle and shovel blade are for illustrative purposes only and form no part of the claimed design.
